OUTBOARD MOTOR DRIVE

Willie E. Huston, Rte. 2, Box P15, Conroe, Tex. 77301

Filed May 20, 1966, Ser. No. 2,483

Term of patent 14 years

(Cl. D71—1)

FIG. 1 is a side elevational view of an outboard motor drive showing my new design, the opposite side thereof being substantially the same in appearance;

FIG. 2 is a front elevational view thereof;

FIG. 3 is a fragmentary isometric view showing the top, front and part of the side opposite the side shown in FIG. 1, and

FIG. 4 is a fragmentary rear elevational view, showing the propeller.

This is a continuation-in-part of design application Serial No. D. 84,543, filed March 31, 1965, and now abandoned.

I claim:

The ornamental design for an outboard motor drive, as shown and described.
